PLUNGER TYPE ELECTRICAL SWITCH

Robert Hetherington, Sharon Hill, Pa., assignor
to Robert Hetherington & Son, Inc., Wilming-
ton, Del., a corporation of Delaware

Application September 15, 1939, Serial No. 295,552

11 Claims. (Cl. 200—76)

My present invention relates to a plunger type electric switch operating through a hollow switch shank.

A purpose of the invention is to accumulate resilient starting energy for a push bar type switch having an impressed starting resistance until the pressure suddenly overcomes the impressed starting resistance for a quick forward movement of the bar.

A further purpose is to provide switch structure of the character indicated that will stay safe under the heavy duty service met on aircraft and be particularly suited to easy and inexpensive manufacture.

A further purpose is to resist hand starting of a hand operated longitudinally movable push bar type switch by spring stops, preferably contact carrying springs, engaging the bar.

A further purpose is to secure a quick break of a resiliently breaking push bar cone-break type switch, using starting longitudinal movement of the bar to concurrently start lateral outward movement away from the cone of contacts at opposite sides of the cone and longitudinal movement of the cone away from the contacts.

A further purpose is to provide novel and inexpensive structure for mounting an annular, preferably conical, contact in cooperative relation with circumferentially spaced internally coned contacts forming parts of an external circuit, to make and break electric connections between the spaced contacts by longitudinal movements of the annular contact and to clean the engagement surfaces between the spaced contacts and the annular contact by rotary movement of the annular contact.

Further purposes will appear in the specification and in the claims.

I have elected to show forms only of my invention that are practical and efficient in operation and which well illustrate the principles involved.

Figure 1 is a longitudinal elevation illustrating a desirable embodiment of the invention.

Figures 2, 3, 4 and 5 are longitudinal sections showing variant forms, each of which could have the same exterior position as Figure 1.

Figure 6 is an enlarged fragmentary section showing detail of one form of the invention.

Like numerals refer to like parts in all figures. Describing in illustration and not in limitation and referring to the drawing:

The illustrated embodiment of the invention may be considered as comprising a three-unit assembly of which the units include three coaxially

connected assemblies, respectively, a main housing assembly, a terminal mount and end housing assembly, and a plunger assembly.

The main housing assembly as shown comprises a hollow metal casing 18, open at one end, with opposite recesses 19 of which one only is shown to accommodate the terminal mount assembly. At the other end it is reduced at shoulder 21 to an externally threaded hollow tubular shank 22 for use in supporting the whole structure from a switchboard or the like, not shown. The shank 22 supports the operating end 23 of a push bar or plunger 24 projecting through the shank. This bar or plunger is of insulating material.

An intermediate portion of the casing 18 is provided with an electrically insulating lining 25—suitably Bakelite. The lining is longitudinally grooved at 26, 26 to receive electrically conducting contact strips 27, 28 which form part of the circuit switched, to insulate them and to support them against circumferential strains and strains diagonal to the lengths of these grooves.

The electrically conducting outer ends of the strips form contacts 31 and are in position for best cooperation with an annular inner contact 32, shown as a cone, mounted upon the plunger assembly. Both the outer and inner contacts are desirably silver.

The bar 24 of the plunger assembly, Figure 1, may form part of a composite plunger. See Figure 2b for one way in which it may be assembled. Intermediate the plunger, along a reduced insulated portion of the plunger are located the inner contact and insulating washers or collars 33 and 34, engaging and insulating the front and back of the contact. These collars, and particularly collar 33 may be used to separate the outer contacts. Collar 35 is fixed in position. Preferably of metal, it allows the plunger to pass through it, surrounds the reduced part 36 of the plunger and receives the thrust of the bar-surrounding spring 37.

The parts of the bar or plunger are threaded together and shouldered in any suitable manner as convenience of manufacture and assemblage make desirable.

Movable contacts of different metals and any other engagement of different metals than rigid fastenings of such parts to each other are avoided and metal parts are desirably made either of silver or of stainless steel, except for the spring contact strips.

When assembled the plunger washer or collar 35 rests upon any suitable supporting wall. At

the opposite end there is a recess within which the head 38 and the plunger near the head are adapted to travel when the operating end is pushed to the left.

The annular inner contact 32, most conveniently of cone shape, is shown pinned at 42 to the push rod. It tapers converging away from the operating end of the push plunger in Figure 2 and toward the operating end in Figures 3, 4 and 5, and in retracted position of the push rod in most of the figures engages the outer contacts 31.

The outer contacts receive current through electrical binding posts 43 and 44.

Retraction of the inner contact takes place toward the right when pressure on the plunger is released.

The terminal assembly as illustrated includes a block 48 of insulation material, suitably Bakelite, bored longitudinally (axially) to receive the plunger and is permissibly closed at the end by a plate 49.

Each of the contact strips 27 and 28 to the rear of the sockets is upwardly turned and dished or grooved at 59 to provide spaced horns or prongs 60 which serve to seat between them and to prevent any sidewise turning of the outside electrical connectors fastened to the binding posts.

Each contact-supporting strip 27 or 28, comprises a thin strip of spring copper or the like. The outer contacts 31 are desirably concave on the faces toward the inner contact for best registry between the contact members.

The switch is suitable for normally closed circuits, using switch forms such as those of Figures 3, 4 and 5 or for normally open circuits, using a switch form such as that of Figure 2, according to the customer's requirements.

The cooperating edges of the contacts and the proper collar (33 in Figures 3, 4 and 5) may be sloped to smooth out the cam action.

By sloping the ends of the outer contacts, as at 70, 70' and sloping the edges of the collars 33, 34, as at 71, 71', outward wedging of the contacts by the collars may be facilitated and the outer contact spacing from the inner contact may be increased without danger of the collar "stubbing" the ends of the outer contacts. The collar and contact cone enter a recess such as 72.

In aircraft service the economy of space effected by providing part of the stroke of the inner contact within the tubular shank is important. It lessens the requisite length of the switch.

When the switch is to be operated to close the circuit and not to open it—the normally open switch of Figure 2—retractive spring movement to the right causes a preferably sloping edge of outer contacts 31 to open the circuit quickly.

In Figure 6 one form of divided plunger is shown. In addition the construction at the right provides for overtravel of the operating mechanism, beyond the length of plunger stroke. The bore 73 and counterbore 74 seat a plate 75 (in the counterbore) within which travels a pin 76 threaded into the cap 77. The cap is pressed outwardly by a spring 78. The cap is free to telescope over the outer part of the plunger, at the same time compressing the spring. If the spring 78 be stiffer than spring 37, pressure upon the cap to the left will operate the plunger first and, with further travel of the operating mechanism, will compress spring 78.

In Figure 2 a normally open switch is shown

in closed position. In Figure 2, (and also in Figures 3, 4 and 5) the spring contact strips are bent inwardly to form knees 79 extending within the path of movement of an insulating collar 80 pinned to the plunger. Spring 37 presses against this collar 80 and builds up a considerable pressure before the knees snap apart and the switch is opened quickly. The separation of the knees spreads the outer contacts away from the inner contact and movement of the inner contact to the right to the end of its stroke carries it wholly beyond the outer contacts. It is then no longer in position to be engaged by the outer contacts no matter how close the spacing of these outer contacts. The long outer surface of the collar 80 maintains the spacing by continuing to keep the knees separated.

Frequently, and it is believed more usually, such switches of normally closed type are hand operated. In those shown in Figures 3, 4 and 5 the requisite hand pressure required to start the switch is stored, as it were, until the resistance presented by the knees of Figures 2, 3, 4 and 5 is overcome, when there is a sudden jump, with first a full release of the restraint.

In Figures 3, 4 and 5 the knees 79 perform the double function of offering spring retardation to opening movement to build up pressure for a quick opening and of causing spreading of the outer contacts for quicker and surer spacing of these contacts from the inner contact and reliably maintaining this space. The collar back of the inner contact is lengthened, as seen at 82, so as, in plunger movement from right to left, to give a rearwardly projecting edge 83 to engage, accumulate pressure against, and finally at a jump to spread the knees and the outer contacts.

The first contact of the long collar with the knees tends to tighten the outer contacts against the inner contact. The long collar surface at 84 ultimately maintains the spacing of the knees. The collars used are rearwardly facing open cups in order to shorten the structure by permitting each spring 37 to extend forwardly within its cup.

In the form shown in Figure 5 the abnormal closed circuit position of the switch parts lies at an intermediate position in the throw of the inner contact and the parts are at open circuit at both extremities of the switch movement. In the normal position of the switch with spring 37 expanded to its full extent the washer 33 is wholly within the recess and the inner contact lies part way within this recess. The outer contacts rest upon the extended collar 84.

At the front end the plunger lies within a recess 85 in a presser sleeve 86 having a flange 87 resting against the shoulder 88 in the recess 72 and the insulated washer 33 rests against the flange 87. Between the plunger end and the closed end 90 of the sleeve 86 lies a spring 89.

The supplemental spring is stiffer than the spring 37. When the parts are moved to the left by pressure upon the end 90 of the sleeve the spring 37 is compressed to the point where the plunger has completed its travel within the switch casing, at which time with further pressure the spring 89 is compressed to give lost motion movement of the parts.

In Figure 14 the flanged sleeve 86', which with an insert serves the purpose of the sleeve 86 is internally threaded to receive an externally threaded thimble 91, closed at 92 to form a ter-

rninal. The thimble can be threaded into the sleeve to different extents according to the extent of projection desired for the closed end of this thimble, determining the point at which operating mechanism begins to move the plunger. The plunger enters the thimble 91 and compresses within it a spring 89 which is stiffer than the spring 37 and thus provides for overtravel. Threading the thimble 91 within the sleeve 86 permits adjustment of the position of the parts at which this plunger end is engaged by operating parts. This adjustment is locked by a collar 93 threaded upon the outside of the thimble 91 and acts as a lock nut against the end of sleeve 86. Having the same outer diameter as the diameter of sleeve 86 this lock nut assists in guiding the sleeve 86 in its travel within the end of the casing shank.

In Figure 2 the inner contact and that part of the plunger carrying it pass within the recess in the tubular shank and a normally open contact is shown when the parts are at rest. The switch is closed by plunger movement to the left. When pressure is released for opening movement retardation against the movement of the plunger is supplied by engagement of the rear edge of the long collar 84 against the knees in the spring contact strips.

In the position shown the knees lie between the inner contact and the collar so that the sleeve must overcome the retardation due to the knees before movement can take place to the right in the figure. When this has been overcome the plunger moves to the right quickly and comes to a stop with the long collar 84 lying between the spring knees, having forced the knees apart and having thus separated the outer contacts. The inner contact comes to rest as far within the recess in the tubular shank as the design contemplates. The knees in this and in later numbered figures may act as spring stops to accumulate pressure for sudden movement in hand operation or act as cams merely.

In Figures 3 and 4 very slightly different normally closed switches are shown, one in closed position and the other open.

The knees rest upon the long collar in this open position and the insulating collar 33 at the same time spreads the contacts or at any rate prevents engagement between the outer contacts and the inner contact.

The form shown in Figure 5 is intended to illustrate the flexibility of the invention. If movement of the plunger to the right be stopped in the position shown it becomes a normally closed contact with provision for quick opening of the outer contacts away from the inner contact by reason of engagement of the long collar with the spring knees of the contact strips. In this case movement of the plunger to the left is provided before the sleeve engages the contact strip knees, taking advantage of the inertia of the moving parts to swell the contact knees outwardly and thus to move outwardly the outer contacts, the washer or collar 33 also engaging the contacts to spread them or preventing them from accidental engagement with the inner contact. If full movement of the plunger to the right be permitted or provided for the recess within the shank forms a resting place for the collar 33 and the outer contacts come to rest upon the insulating operating sleeve. Ultimate movement of the contact sleeve to the left introduces lost motion, permitting a considerable variation in the stopping point of the operating

mechanism without interference with a standard movement of the switch-engaging parts.

When the plunger comes forward into the recess within the tubular shank, then the switch is normally open with the outer contacts resting upon the long sleeve; and subsequent movement of the contact to the left provides, first engagement of the outer and inner contacts to close the circuit at an intermediate portion of the stroke, and finally opens the circuit again at the left end of the stroke.

It will be evident that the knees of the contact strips may be used either to offer retardation to movement until the pressure is accumulated, or may provide merely for lifting the knees as cam surfaces in a normal relatively smooth working movement of the switch, but normally performs both functions.

It will be evident that the character of action of the knees, whether with accumulating resistance leading to a jump operation or as a cam spreader merely, will depend in large measure upon whether the operation is to be hand-operation or machine-operation, the cam form being better suited to machine operation than the other.

In view of my invention and disclosure variation and modification to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention what I claim as new and desire to secure by Letters Patent is:

1. A switch having a spring opposed operating plunger, a casing for the switch, an inner contact carried by the plunger and outer contacts within the path of movement of the inner contact adapted to be engaged with movement of the plunger, spring supporting strips for the outer contacts having inwardly extending portions intermediate their lengths for engagement by cam means, insulation between the spring supporting strips and the casing, and cam means in front of and also in the rear of the inner contact engaging respectively the outer contacts and the inwardly extending portions of their supports to wedge the contacts apart during movement of the plunger.

2. A switch having a spring opposed operating plunger, a casing for the switch, an inner contact carried by the plunger and outer contacts within the path of movement of the inner contact, adapted to be engaged with movement of the plunger, spring supporting strips for the outer contacts, insulation between the spring supporting strips and the casing, inwardly directed knees in the contact strips, insulating means carried by the plunger engaging the knees to separate them and insulating means carried by the plunger and at one limit of plunger stroke entering between the outer contacts and separating these contacts.

3. A switch having a spring opposed operating plunger, a casing for the switch, an inner contact carried by the plunger and outer contacts within the path of movement of the inner contact, adapted to be engaged with movement of the plunger, spring supporting strips for the outer contacts, insulation between the spring supporting strips and the casing, inwardly directed knees in the contact strips, insulating means carried by the plunger engaging the knees to separate them

to offer spring retardation to the plunger movement with subsequent jumping of the plunger and separation of the outer contacts and insulating means carried by the plunger and at one limit of the plunger stroke adapted also to separate the outer contacts.

4. A switch having a spring opposed operating plunger, a casing for the switch, an inner contact carried by the plunger and outer contacts within the path of movement of the inner contact, having inwardly extending portions adapted to be engaged with movement of the plunger, spring supporting strips for the outer contacts, insulation between the spring supporting strips and the casing, and cam means carried by the plunger in front of and also in the rear of the inner contact engaging respectively the outer contacts and their supports to wedge the contacts apart during movement of the plunger and to hold them in separated position.

5. A switch having a spring opposed operating plunger, a casing for the switch, an inner tapered contact carried by the plunger and outer contacts within the path of movement of the inner contact adapted to be engaged with movement of the plunger, spring supporting strips for the outer contacts, insulation between the spring supporting strips and the casing, a hollow tubular shank for attachment of the switch, interiorly recessed to receive the forward end of the inner contact and an insulating washer carried by the plunger adjacent the smaller end of the contact and of larger diameter than that of the said smaller end, normally resting within the shank and adapted to engage the outer contacts and hold them apart.

6. In a switch, a longitudinally movable operating plunger, a spring surrounding the plunger and opposing its movement, an inner contact carried by the plunger, outer contacts within the path of movement of the inner contact and adapted to be engaged by it with movement of the plunger, spring supporting strips for the outer contacts, a casing, insulation between the spring supporting strips and the casing, inwardly directed cam knees carried by the supporting strips and insulating means surrounding one end of the spring and surrounding the plunger, carried by the plunger, and engaging with the cam knees to wedge the outer contacts apart and out of engagement with the inner contact and hold them apart.

7. In a plunger switch, a longitudinally movable operating plunger, a spring surrounding the plunger, insulation surrounding one end of the spring, an inner contact surrounding the plunger in front of the insulation, the contact being tapered forwardly and inwardly, a pair of outer contacts fitting the taper of the inner contact, spring fingers supporting the outer contacts and having inwardly directed cam knees adapted to

be engaged by the insulation and a casing by which the outer contact fingers are supported and from which they are insulated.

8. A switch casing, insulation within the casing, spring fingers carried by the insulation and having inwardly directed cam knees, outer contacts carried by the fingers in front of the knees and sloping with respect to each other, a plunger, a tapered inner contact having a slope corresponding to the slopes of the outer contacts, an insulating thimble carried by the plunger, and a spring having one end engaging the inside of the thimble, opposing movement of the plunger and permitting the spring to be compressed, and the thimble brought into engagement with the knees.

9. In a switch, a casing, a longitudinally movable plunger guided therein, insulation within the casing, outer contact fingers supported from the insulation, outer contacts carried by the fingers and sloping with respect to each other, and an inner contact carried by the plunger and tapered forwardly and inwardly to correspond with the slope of the outer contacts, inwardly directed knees in the outer contact fingers, insulation carried by the plunger at the rear of the inner contact adapted to engage the knees, and insulation carried by the plunger in front of the inner contact and of larger diameter than the front end of the inner contact, adapted to hold the outer contacts spaced from the inner contact.

10. A switch having a longitudinally movable plunger, a spring surrounding the plunger and opposing its movement, an inner contact carried by the plunger, outer contacts engaging the first contact, insulation carried by the plunger, springs supporting the outer contacts and engaged by the insulation during movement of the plunger, adapted to oppose movement while pressure is being built up in the plunger and then snap outwardly to permit plunger movement, said springs providing cam means separating the outer contacts with movements of the plunger, and a casing about the plunger supporting the outer contacts through the springs.

11. A switch having a spring-opposed longitudinally movable operating plunger, a casing for the switch, an inner contact carried by the plunger, outer contacts engaging the inner contact, springs supported by the casing, carrying the outer contacts and themselves within the path of movement of the inner contact, adapted to be engaged with movement of the plunger, cams located within the spring, and separate insulating means, one normally in front and another normally behind the outer contacts in direction of plunger movement, movable with the inner contact and respectively holding the outer contacts apart and engaging the spring supported cams to separate the outer contacts at one limit of movement of the switch.

ROBERT HETHERINGTON.
